UNITED STATES PATENT OFFICE.

FRANCIS DONALDSON, OF PITTSBURG, PENNSYLVANIA, ASSIGNOR TO LIDGERWOOD MANUFACTURING COMPANY, OF NEW YORK, N. Y., A CORPORATION OF NEW YORK.

WINDING-DRUM.

No. 909,768.

Specification of Letters Patent.

Patented Jan. 12, 1909.

Application filed February 23, 1907, Serial No. 358,987. Renewed December 5, 1908. Serial No. 466,167.

To all whom it may concern:

Be it known that I, FRANCIS DONALDSON, of Pittsburg, in the county of Allegheny, and in the State of Pennsylvania, have invented a certain new and useful Improvement in Winding-Drums, and do hereby declare that the following is a full, clear, and exact description thereof, reference being had to the accompanying drawings, in

10 which—

Figure 1 is a vertical sectional view of a portion of a hoisting engine embodying my invention; Fig. 2 is an end view of Fig. 1; and Figs. 3 to 8 are detail views.

15 The object of my invention has been to provide a winding drum and driving gearing for hoisting engines, pile drivers, etc. in which the wear shall be so provided for that there is little danger of serious injury 20 through lack of lubrication; and to such ends my invention consists in the winding drum hereinafter specified.

The winding drums of hoisting engines, pile drivers, etc., have, prior to my invention, so far as I am aware, been so constructed that the drum rotates upon its shaft, and the journals of the shaft upon which the drum rotates are necessarily more or less difficult of access, so that the lubrication of 30 such journals is occasionally overlooked, with the result that there is very serious wear and heating between the drum and its shaft, and occasionally such serious injury occurs that the drum has to be replaced. 35 The constant pull of the rope wound about the winding drum, whether or not hoisting is being done, causes a lateral pull of the drum on its shaft that makes the wear between the drum and shaft very heavy unless 40 the lubrication is good. When such wear occurs, it renders the machine useless for the time being and will frequently prevent the working of a large force of men while the machine is being repaired. By my invention 45 the drum is fixed on its shaft, and all such trouble is avoided.

In that embodiment of my invention illustrated in the accompanying drawings, the drum 10 is keyed to its shaft 11, the shaft 50 being supported at its ends in bearings on the frame of the machine. A gear 12 is journaled on the shaft, and is free to turn thereon except when it is clutched to the drum as later described. Anti-friction washers 13 55 may be placed between the gear and the hub

of the drum. On the inside of the rim of the gear are formed a series of slots 14 in which are received fins 15 on a clutch-member 16. The clutch-member comprises a flange 17 having the fins 15 formed thereon, 60 and also having radial arms 18 preferably formed in one piece with the fins and flange, the said arms having a plate 19 bolted to them. A ring 20 is supported by the flange and is provided with a series of sockets 21, 65 in which are mounted the shanks 22 of beveled friction blocks 23. The annular series of friction blocks practically forms a cone which is adapted to be forced into the conical recess formed within a flange on the adjacent drum-head, a friction clutch thus being formed. In order to normally separate the clutch-members, and also to hold the gear against the anti-friction washers, 70 springs 23^a are interposed between the plate 75 19 and the gear, such springs being preferably flat springs, as shown.

In order to force the members of the friction clutch together, the following means are provided: A collar 24 is loosely mounted 80 on the shaft against the plate 19, and for convenience of renewing the blocks of the friction clutch as later described, the said collar is made in two parts and united by bolts. A slot 25 is formed in the shaft, and 85 a key 26, narrower than the said slot, is mounted in the latter, the key being held in place by a cotter at each end. A hole 27 is formed in the shaft and a rod 28 is inserted in the said hole. The collar 24 is preferably 90 provided with a slot 29 in which the key is fitted. A force oil-cup 30 may be secured upon the gear and connected with a pipe 31 running through the hub to supply oil for the gear. 95

In the operation of my drum, the gear is constantly driven by the engine. The shaft remains stationary until it is desired to raise or lower the load. When it is desired to raise the load, the rod 28 is forced inward 100 by any desired means, causing the key, the split collar, the plate and the inner member of the friction clutch to move toward the drum, and thus causes the clutch to engage the drum and shaft to rotate with the gear. 105 When it is desired to lower the load, or to stop the hoisting, the rod 28 is withdrawn, and the springs spread the clutch-members, causing the drum and shaft to cease to revolve. 110

It will be observed that as the drum is fixed upon the shaft in my construction, there can be no wear between such parts. Where, as in the ordinary construction, the drum revolves on the shaft there is always serious wear, whether or not hoisting is being done, because in such construction, the shaft is constantly rotating, and as the hoisting rope is always pulling on the drum, even though the drum be not revolving, there is a heavy side strain of the drum on the shaft, causing wear. If, as frequently happens, the journals of the drum on the shaft are not oiled, there may be serious injury within a short time, and the engine has to be practically dismantled to make repairs.

While my gear is loose on the shaft, it will be observed that it has no longitudinal movement on the shaft, but it is only the clutch-member which is carried by the gear that has such movement. When the drum is not being revolved, the only wear which is taking place in my construction is that of the gear on its journal, and, as there is no strain on the gear at such time, such wear amounts to little. When there is no hoisting being done, the drum is stationary on the shaft, and the shaft is stationary in its main bearings.

30 The blocks of the friction clutch can readily be renewed in the construction which I have invented. It is only necessary to separate the parts of the split collar, and to remove the collar, and also, if necessary, the key (the latter being removable upon taking out one of its cotters), when the gear and its attached clutch-members can be moved away from the drum sufficiently to permit ready access to the blocks.

40 All of the bearings of my construction are easily oiled. They consist only of the main bearings of the shaft, and of the journals of the gear. The split collar forms a sort of cylinder-head to the cylinder formed by the hub of the plate 19, and the back and forth movement of the collar and plate serve to force oil in and out of the journal of the gear.

While I have described what I consider to be the best embodiment of my invention, I desire it to be understood that the principles can be embodied in different forms, and I desire not to be limited beyond the requirements of the prior art, and the terms of my claims.

Having thus described my invention, I claim—

1. In a hoisting apparatus, the combination of a shaft, a drum fixed on said shaft, a clutch-member mounted on said drum, a gear journaled on said shaft, a clutch-member splined within said gear, springs interposed between said clutch-member and said gear, said springs tending to hold said gear against said drum and to withdraw the

clutch-member from the drum, and means for forcing said gear clutch-member toward said drum.

2. In a hoisting apparatus, the combination of a shaft, bearings therefor, a drum fixed on said shaft, a friction clutch member carried by said drum, a gear journaled on said shaft, a friction clutch member carried by said gear, one of said members having a series of removable friction blocks, 70 readily removable means interposed between one of said bearings and one of said friction clutch members for moving said clutch member, the space between said clutch member and the adjacent bearing being at least as 75 wide as said friction blocks, whereby upon withdrawing said removable means, said friction clutch members may be sufficiently separated to remove said friction blocks.

3. In a hoisting apparatus, the combination of a shaft, bearings therefor, a drum fixed on said shaft, a female friction clutch member carried by said drum, a gear journaled on said shaft close to said drum, a male friction clutch member carried by said 85 gear, said last-mentioned member having a series of removable blocks, means interposed between said last-mentioned member and the adjacent bearing for moving said member, said means for moving being removable, and 90 the space between said last-mentioned member and said bearing being equal at least to the width of said removable blocks, whereby said gear and its clutch member may be withdrawn to permit the removal of said friction 95 blocks.

4. In a hoisting apparatus, the combination of a shaft, bearings therefor, a drum fixed on said shaft, a gear journaled on said shaft close to said drum, a male friction clutch member carried by said gear, said last-mentioned member having a series of removable blocks, means interposed between said last-mentioned member and the adjacent bearing for moving said member, said means for moving being removable, and the space between said last-mentioned member and said bearing being equal at least to the width of said removable blocks, whereby 105 said gear and its clutch member may be withdrawn to permit the removal of said friction blocks, said means for moving said male friction clutch member comprising a split collar mounted on the shaft, a key 110 mounted in a slot in the shaft and bearing against said split collar, and a rod longitudinally movable of said shaft and bearing against said key.

5. In a hoisting apparatus, the combination of a shaft, bearings therefor, a drum fixed on said shaft, a female friction clutch member carried by said drum, a gear journaled on said shaft close to said drum, a male friction clutch member carried by said 125 gear, said last-mentioned member having a series of removable blocks, means interposed between said last-mentioned member and the adjacent bearing for moving said member, said means for moving being removable, and the space between said last-mentioned member and said bearing being equal at least to the width of said removable blocks, whereby 130 said gear and its clutch member may be withdrawn to permit the removal of said friction blocks, said means for moving said male friction clutch member comprising a split collar mounted on the shaft, a key mounted in a slot in the shaft and bearing against said split collar, and a rod longitudinally movable of said shaft and bearing against said key.

gear, said last-mentioned member having a series of removable blocks, means interposed between said last-mentioned member and the adjacent bearing for moving said member, 5 said means for moving being removable, the space between said last-mentioned member and said bearing being equal at least to the width of said removable blocks, whereby said gear and its clutch member may be withdrawn to permit the removal of said fric-

tion blocks, and a spring interposed between said male clutch member and said gear to hold said gear against said drum.

In testimony that I claim the foregoing I have hereunto set my hand.

FRANCIS DONALDSON.
